MEANS FOR FOLDING FLAT ARTICLES

Samuel William Lister, London, England

Application February 10, 1949, Serial No. 75,690
In Great Britain February 10, 1948

2 Claims. (Cl. 270—94)

1

This invention relates to means for folding flat articles.

It is particularly concerned with the automatic folding of flat articles which are delivered to a folding location one after the other in varying widths and/or lengths or at varying distances from a reference point, or both in varying widths and/or lengths and at varying distances from the reference point, so that the articles will all be folded in the same predetermined manner relative to their width. An example of the type of work concerned is laundry flat work, such as sheets, tablecloths, towels, handkerchiefs and so on, as delivered from an ironing machine. The articles delivered from this machine may vary considerably in size and, due to the manner in which they are fed into the machine, they may be variously disposed in the direction of their width.

The main object of this invention is to provide improved and simple means for automatically folding flat articles of the character indicated.

According to the invention, means for folding flat articles comprises a suitable shaped former over which the articles are fed by conveyor tapes or bands so that the parts of each article at opposite sides of the desired fold line are progressively turned about this line to come together in face-to-face contact.

The flat articles after having been folded once by the aid of the means indicated above, may pass to a second folding means of the same character arranged to fold the articles along a line parallel with the fold first produced. Means is, with advantage, provided whereby the flat articles passing to the first folding means, or the folded articles passing to the second folding means, as the case may be, may be adjusted transversely of their path of travel relative to the respective folding means so that the fold to be produced by the aid of the latter may be formed at the desired location in the width of the article.

From the first folding means, or from the second folding means when this is provided, the folded article may pass to an additional folding appliance of a known character adapted to fold the article again but in a direction at right angles to the earlier folds.

The nature of the invention will be clearly understood from the following description of an example of a machine which may be employed to carry the invention into practical effect, reference being made to the accompanying drawings. It should be understood, however, that these drawings are somewhat diagrammatic although they clearly indicate the construction and functioning of the folding means which constitutes the main feature of the present invention.

In the drawings:

Fig. 1 is a perspective view taken from above and in the front of a machine embodying two

2

folding means constructed in accordance with the invention, some parts being omitted or broken away.

Fig. 2 is a side elevation of the first folding means, part of one of the conveyor bands thereof being broken away.

Fig. 3 is a front elevation of the first folding means,

Fig. 4 is a section taken on the line IV—IV of Fig. 3,

Fig. 5 is a perspective view, taken from the rear, of the first folding means, parts being omitted or broken away, and

Fig. 6 is an elevational view of the second folding means, taken from the front of the machine.

Referring to Fig. 1, the machine comprises a main endless conveyor, indicated generally by the reference A, composed of parallel tapes, strings or the like which extends horizontally from a fixed feeding location B to a fixed first folding location C. The feeding location B (as shown) may be the delivery end of a flat work ironer (or of the drying machine which generally follows such an ironer), the sheets, tablecloths and so on, indicated by the reference D and referred to herein simply as "sheets," being fed in succession on to the main conveyor A in a somewhat haphazard fashion relative to the side edges of the conveyor but all with their leading edges disposed substantially at right angles to the length of the conveyor.

At the first folding location C is arranged folding means, including a folding former to be described, which receives the flat sheets from the main conveyor A, folds them about a longitudinal line and delivers them to a secondary conveyor E which, in turn, carries the once-folded sheets

25 to a fixed second folding location F. Here the sheets are again folded about a longitudinal line and delivered on to a third conveyor G which may carry the twice-folded sheets over a transverse folder (not shown) of any suitable known type.

In order to simplify the description of the machine, it will be assumed that each longitudinal

35 fold to be made is to come at the centre of the width of the sheet or folded sheet, as the case may be, although folds may be produced at other locations without difficulty as will become apparent from the following description.

40 The main conveyor A comprises a set of parallel tapes, strings or the like 1 extending between and passing around a pair of spaced parallel rollers 2 and 3, one of which is continuously driven (by means not illustrated) to cause the

45 upper runs of the tapes to travel towards the folding location C. The rollers 2 and 3 are mounted at the respective ends of a carriage 4 which is mounted for translating motion, trans-

50 versely of the direction of travel of the tapes 1, by means of wheels 5 running on guide rails 6.

55

60

65

70

75

85

The displacement of the carriage 4 is effected by any suitable servomotor mechanism (not illustrated) which is controlled by means of a hand-wheel 7 adapted to be actuated appropriately by an operator stationed on the platform 8 provided on the carriage 4 near the front end thereof. This operator observes the sheets D as they travel along the conveyor A and adjusts the position of the carriage 4 along the rails 6 in such a sense as to ensure that the longitudinal centre line of each sheet will be located in the same vertical plane as the centre line of the folding means at the location C before the sheet enters this means. The observation and correct positioning of the sheets travelling over the carriage is facilitated by the provision of a gauge bar 9 of angle section which is supported horizontally on a fixed position close above the upper runs of the tapes 1 and carries a central reference mark 10 indicating the correct position of the centre line of the sheet. At each side of the mark 10 the bar 9 carries a series of graduations 11, the areas between which are clearly distinguished by different colorations or the like, so that any two areas which are equally spaced from, and on appropriate sides of, the mark 10 may readily be recognised as corresponding with each other. The operator, therefore, merely has to bring the carriage to a position in which the longitudinal edges of the sheet D run beneath corresponding areas on the bar 9 in order to centralise the sheet on the mark 10. It will be understood that a guide or support member (not shown) will be provided to bridge the gap between the delivery end of the flat work ironer, or of the drying machine, at the location B and the intake end of the conveyor A, and that a similar provision will be made at the delivery end of the conveyor A to guide the sheets from the latter on to conveying means incorporated in the folding means now to be described.

The folding means at the first folding location C embodies a fold former which comprises a form 12 of sheet metal or other material having a lower rectilinear edge 13 disposed parallel with and just below the level of the upper run of the main conveyor A but spaced somewhat from its delivery end. The gap between the lower edge 13 of the form 12 and the conveyor A is partly bridged by the forwardly extending parts of the conveyor bands yet to be described and the remainder of the gap may be filled by a suitable delivery chute or guide plate as has just been indicated. The form 12 is tetrahedral in shape (see Figs. 2, 3, 4 and 5) with an upper edge 14 disposed parallel with the plane containing the upper surface of the conveyor A but located at right angles to a vertical plane containing the lower edge 13 of the form. Rear edges 15 (Fig. 2) of the form join the ends of the lower edge 13 to the rear end of the upper edge 14, i. e. that end more remote from the conveyor A, and front edges 16 (Figs. 3 and 5) join the ends of the lower edge 13 to the other or front end of the upper edge 14. The dimensions of the tetrahedron are such that the sum of the distance between any point on a rear edge 15 and the upper edge 14, measured parallel with the corresponding front edge 16, and the distance between the same point and the lower edge 13, measured parallel with the line joining the centre of the lower edge 13 to the rear end of the upper edge 14, is constant and equal to the length of the front edge 16.

Parallel with, and one on either side of, the

upper edge 14 of the form 12 are two closely spaced small diameter guide rollers, 17 and 18, the roller 17 being located as close to the edge 14 as is practicable and the roller 18 being located at a slightly higher level, see Figs. 3 and 5. A larger diameter driven roller 19 is arranged parallel with but forwardly of the lower edge 13 of the form 12 and a smaller diameter guide roller 20 is spaced vertically beneath but parallel with the edge 13. Two inclined guide bars 21 are disposed V-fashion below the form 12 with their upper ends closely adjacent and just rearward of the centre of length of the guide roller 20. From these ends the bars diverge downwards and rearwards, as shown in Figs. 1 and 5. Extending forwardly from near the lower end of each inclined bar 21 is a lower guide roller 22 having its axis parallel with the upper edge 14 of the form. Parallel with but just outwardly of each roller 22 is a further lower guide roller 23 and vertically above each of the rollers 23 is arranged an upper guide roller 24 having its axis disposed parallel with and substantially in the same horizontal plane as the upper edge 14 of the form. Two endless conveyor bands 25 and 26 each equal in width to half the length of the lower edge 13 of the form 12, are threaded around the driven roller 19, the guide rollers 20, 22, 23, 24, and the bars 21, as shown in Figs. 1 and 5. It will be seen that the inner edges of those parts of the bands 25, 26 running over the rear face of the form travel in contact with each other along the vertical medial line of this face while their outer edges travel along the front edges 16 of the form. Each conveyor band 25 or 26 passes away from the upper edge 14 of the form, over the appropriate guide roller 17 or 18 closely adjacent to this edge, to move outwards to the corresponding upper guide roller 24. The band 25 (on the delivery side) travels downwards to the corresponding lower roller 23 from which it passes to the roller 22 and thence around the inclined guide bar 21 to wrap half the length of the upper part of the roller 20 which is parallel with the lower edge 13 of the form. The other band 26 travels downwards from its upper roller 24 to the corresponding lower roller 23 and thence over the roller 22 and the corresponding inclined bar 21 to wrap the other half of the length of the upper part of the roller 20. Both bands, then edge-to-edge, pass around the driven roller 19 before passing over the rear and side faces of the form again. It should be noted that each band 25 or 26 is twisted face-to-face and edge-for-edge during each passage through the path just defined.

A sheet D delivered from the main conveyor A to the upper surface of the apron-like portion of the two bands 25, 26 extending from the roller 19 to the lower edge 13 of the form, is brought to the latter by the motion of the bands to be introduced into the space between the form and the bands. A sufficient lead-in may be secured by rounding the lower edge 13 of the form but a guide plate somewhat similar to that used in the second folding means may be provided if desired. The sheet D is fed by the endless bands 25, 26 over the form 12 with a progressively increasing turning forwards of the leading corners of the sheet. Eventually, the leading edge of the sheet D arrives at the upper edge 14 of the form with its ends disposed on this edge near the front end thereof. If the sheet approached the form with its longitudinal centre line in the vertical plane containing the upper edge of the form, the leading edge 75 of the sheet will be folded in two, see Figs. 1, 2

and 5. As the feeding of the sheet is continued by the endless bands 25, 26, the folding of the sheet progresses and the folded end falls on to the band 25 at the delivery side, due to the slight staggering of the rollers 17 and 18 relative to the upper edge of the form, to be conveyed by the band 25 to the discharge point constituted by the return of the band around the appropriate upper guide roller 24.

The discharge point is located closely adjacent to one return roller of the endless conveyor E, running in the same general direction, which receives the folded sheet from the delivery band 25 and transports it to a second endless conveyor 27 which feeds the longitudinal folding means at the location F. This means is exactly similar in construction to the folding means just described and the corresponding parts thereof are indicated by the same reference numerals as applied in the preceding description but with the suffix "a" added. It should be pointed out, however, that (1) the second form 12a is inverted with respect to the first form 12, so that it is fed from the top end and delivers at the bottom, (2) the overall width of the second form 12a is only about half that of the first form 12, because it has to deal with sheets D which are already once folded, and (3) the edge 14a of the form 12a is disposed in a vertical plane which is at right-angles to the vertical plane containing the edge 14 of the first form 12. The second form 12a delivers the twice folded sheets D on to a horizontal endless conveyor G which feeds them to a transverse folder which is of known type and therefore not illustrated.

Owing to the inversion of the second form 12a, in relation to the position of the first form 12, a support 28 (Fig. 6) is provided to extend forwards from the edge 13a of the form parallel with and just below the apron portion of the bands 25a and 26a. This support 28, which may be a polished plate, extends beneath the delivery end of the conveyor 27 and serves to guide the folded sheets from the latter to the form 12a.

It will have been appreciated that the first fold former 12 is positioned correctly in relation to a sheet D being delivered from the main conveyor A, so that it will cause the sheet to be folded in half, due to the adjustment of the position of the carriage 4 under the control of an operator.

The second fold former 12a must also receive the folded sheet from the first fold former 12 in the correct position to produce a further central longitudinal fold therein. Suitable means for effecting this comprises a servo-motor mechanism (not shown) for displacing the conveyor E transversely under the control of an operator stationed at such a location that he may observe the folded sheets as they pass over the conveyor E. As before, a fixed gauge bar 29 is provided above the conveyor E and carries a mark 30, indicating the correct centre line position, flanked on each side by corresponding sets of coloured graduations or the like 31. The operator may thus readily centralise the folded sheets as they pass to the conveyor 27.

The main conveyor A may, of course, be of the wide endless band type instead of the parallel-tapes type shown.

What I claim is:

1. Means for folding flat articles comprising a symmetrical tetrahedral former having a face of largest superficial area twice as large as either

of two equal sized contiguous faces which meet at an apex of the said largest face opposite to a base edge thereof, a pair of endless bands each of a width approximately one-half that of said base edge, each of said bands being supported for continuous movement in unison in a closed loop path, means for directing said bands in side by side relation in a first plane across said base edge of said former and then changing the plane of said bands so that said bands are brought in face to face relation at the apex by causing them to traverse the faces of said former thus twisting said bands 90°, spaced guide means paralleling said apex for leading each of said bands laterally away from said apex in opposite directions therefrom, thence in generally parallel planes to a level beyond said base edge, and thence reversing the direction of movement of said bands to direct them from said last-mentioned level toward said base edge and at the same time twisting said bands 90° to bring said bands into side by side relation in a plane paralleling said base edge.

2. Means for folding flat articles comprising a symmetrical tetrahedral former having a face of largest superficial area twice as large as either of two equal sized contiguous faces which meet at an apex of the said largest face opposite to a base edge thereof, a pair of endless bands each of a width approximately one-half that of said base edge, each of said bands being supported for continuous movement in unison in a closed loop path and adapted to feed the articles over the largest face of said former from the base edge thereof so that the parts of the article to be folded at each side of a desired fold line are progressively turned and run over the corresponding contiguous faces and will leave these in face to face contact with each other, means for directing said bands in side by side relation in a first plane across said base edge of said former and then changing the plane of said bands so that said bands are brought in face to face relation at the apex by causing them to traverse the faces of said former thus twisting said bands 90°, spaced guide means paralleling said apex for leading each of said bands laterally away from said apex in opposite directions therefrom, then in generally parallel planes to a level beyond said base edge, and thence reversing the direction of movement of said bands to direct them from said last-mentioned level toward said base edge and at the same time twisting said bands 90° to bring said bands into side by side relation in a plane paralleling said base edge, whereby the face of each band which is nearer to the former during one traverse of the band over the former becomes the face of the band which is farther from the former during the subsequent traverse of the band over the former.

SAMUEL WILLIAM LISTER.
